UNITED STATES PATENT OFFICE.

HERMAN FRASCH, OF LONDON, ONTARIO, CANADA.

PROCESS OF AND APPARATUS FOR DISTILLING HYDROCARBON OIL.

SPECIFICATION forming part of Letters Patent No. 340,499, dated April 20, 1886.

Application filed November 11, 1885. Serial No. 182,486. (No model.)

To all whom it may concern:

Be it known that I, HERMAN FRASCH, a citizen of the United States, residing at London, in the Province of Ontario, Canada, have 5 invented certain new and useful Improvements in the Process of and Apparatus for Distilling Hydrocarbon Oils, of which the following specification is a full, clear, and exact description.

10 This invention relates more particularly to the distillation of petroleum and other hydrocarbon oils for the purpose of obtaining fluids for burning; but it is not wholly nor strictly limited thereto.

15 In the distillation of petroleum or similar hydrocarbon the gradual rising of the boiling-point of the liquid in the still and the decomposition which takes place as the temperature increases cause the resulting distillates to 20 consist of light and heavy products having widely different boiling-points. The light liquids cause the distillates to have a low fire-test, while the presence of the heavy liquids injure the burning qualities of the oil. These 25 effects are produced even when the proportions of light and heavy oils present are small. Moreover, during the whole run a small quantity of the boiling oil is carried over mechanically by the current of vapor, and this causes 30 difficulty in burning, and gives a greenish or yellow tint to the distillate.

35 The object of the present invention is to prevent this mechanical carrying over of the liquid distilling, and also to separate the vapors, so as to obtain the desired grades of oil by simpler, cheaper, and more efficient means than heretofore employed.

40 To prevent the mechanical carrying over of the oil, many devices have been employed, generally based upon the alcohol still, and consisting of perforated plates, through which the vapors are passed. These plates, while they may answer with gasoline or benzine, are unsuited where hydrocarbons boiling at 45 two hundred degrees Fahrenheit (200° F.) and above are distilled, because their vapors are so sensitive to the abstraction of heat, especially if in the presence of a liquid hydrocarbon, that even one plate is liable to cause 50 so much condensation thereof as seriously to hinder the operation of the still. Moreover,

the resistance offered by the plate is often too great to render their use safe.

According to the present invention the still is provided on top with a dome filled or partly 55 filled with a mass of broken limestone or coke or other material in irregular blocks or pieces, (preferably irregular in shape and about four or five inches in diameter,) and the hot vapors before or as they leave the still are 60 passed through this mass. The channels through the stone being irregular and angular, cause the vapors to pursue a tortuous course, which induces the deposit upon the stone (or other material) of particles held in suspension 65 thereby. Those particles collect and run together and drop back into the still. The stone rests upon a grating that forms the base of the dome, and separates it from the interior of the still. The diameter of the dome is so large 70 that no sensible resistance to the passage of the vapors is caused by the stone therein. The height of the dome is small, preferably somewhat less than the diameter. The vapors escape at the top of the dome.

75 To separate the vapors from the different grades of oil, a column, or, better, a number of parallel columns, which are or may be surrounded by or immersed in a medium of proper temperature—such as hot water, for 80 example—is provided, each column having inside a succession of rings and disks arranged alternately, so that the vapors are compelled to pursue a tortuous course over and in contact with them. Vapors condense on the disks 85 and rings, and the liquid falls in streams from disk to ring and ring to disk through the upward-passing vapor. The condensed hot liquid thus acts as a direct condenser of the still hotter vapor. On account of the high temperature of the condensed liquid only heavy 90 vapors are condensed, the remainder passing onto a second column or group of columns of similar construction, or into any suitable condenser. The condensed liquids are or may be 95 drawn off separately from each column. The temperature of the columns is regulated to produce the desired grade of oil. Where it is desired to obtain a number of grades of different fire-test, the temperature is diminished 100 for each successive column by the use of condensing media of lower temperature or other-

wise. Different grades can also be obtained from the same column by dividing it into sections and tapping them separately, the temperature becoming lower as the vapors lose the heat received in the still, although the surrounding medium may be of the same temperature, or even be warmer about the higher sections. The oil from the lowest section has often a fire-test considerably higher—say three hundred degrees Fahrenheit (300° F.)—than the temperature of the surrounding water, which may be about two hundred and twelve degrees (212° F.) Where a group of columns is used, they are preferably connected with a common manifold, with which the vapor-outlet from the still is connected. A cold water condenser is or may be used to condense the last or lightest vapors, and it may at the same time be utilized to cool the products condensed in the columns. The rings and disks are preferably united into a system, and suspended within the columns, which is or may be a simple cast-iron pipe. These constructions, which have been indicated as being preferably employed, constitute special improvements, it being, however, also understood that other and more general improvement not limited to these special constructions are also included in the invention.

The following is a description of what is considered the best mode of applying the principle of the invention, reference being had to the accompanying drawings, which form a part of this specification, and show an apparatus for producing three grades of oil.

Figure 1 is a longitudinal sectional view of the apparatus, (including the still,) and Figs. 2 and 3 longitudinal and cross-sections, respectively, of the condensing-columns and their accessories. In Fig. 2 the section is taken on a different plane from that of Fig. 1, so as to show the interior construction of the columns. Figs. 4 and 5 are detail views.

The still A, which may be of any ordinary or suitable form, heated in any ordinary or suitable manner, but which, as shown, is heated by direct fire-heat, is provided with a dome, B, on top. This dome is filled or partly filled with the mass C of irregular broken limestone or coke or like material. Its bottom is formed of a grating, D, upon which the mass C rests. The vapor-escape pipe E leads from the top of this dome, the vapors passing from the still through the mass C of broken material, upon which any particles held mechanically in suspension are deposited, and from which they fall back into the still. The broken stone C, being practically at the temperature of the still, does not effect any considerable condensation of the vapors, and the oil which drips back, being practically at the temperature of the boiling oil below, does not check the distillation. The dome is broad and low—say four and a half feet (4½ ft.) in diameter and three and a half feet (3½ ft.) high for a five-hundred barrel (500 bbl.) cy-

lindrical still—so that the stone therein does not offer any substantial resistance to the escape of the vapors.

The pipe E conducts the vapors into the fractionating condenser. This apparatus consists of a manifold, G, and columns H, with their inlets and outlets, and the box R, in which they are placed. The pipe E is connected by a downward bend with the middle tubule of the manifold G. The columns H are connected with tubules on either side of the middle, and each column is divided into two sections by a bend or offset about the middle of the same. Each section is fitted with a system of rings, I, and disks K. Those are strung upon suspension or tie rods L, (see Fig. 4,) the disks being provided with ears for the purpose, (see Fig. 5,) and are separated by sleeves M. A plate or frame at the top, which is or may be one of the disks or rings, extends over the edge of the pipe, which forms the column or of a flange thereon. The system of intercepting rings and disks is suspended from this plate or frame. The suspension of the system permits it and each part of it to expand and contract freely. The diameter of the disks is somewhat greater than the interior diameter of the rings, so that their edges overlap.

The pipe N, provided with a trap, is connected with the bottom of the manifold G, for drawing off the oil which collects therein. A pipe, P, provided with a trap, is connected with the upper section of each column H at the bottom of the section for drawing off the lighter oil which is condensed in said upper section.

From the top of each column a pipe, Q, conducts away the uncondensed vapors. The manifolds and columns are contained in a box, R, which is filled with hot water or other medium for moderating the temperature in the fractional condenser. For producing oil having a fire-test of, say, three hundred degrees Fahrenheit (300° F.), boiling water may be used; but a higher or lower temperature may be used, according to the quality of the oil which it is desired to obtain. The temperature of the water may be maintained uniform by any ordinary or suitable means. By using hot water or a medium above ordinary atmospheric temperature, and approximating more or less that of the vapors to be condensed, the amount which the vapors will be cooled in passing through the fractional condenser can be limited.

The pipes N P Q are all connected with coils or cooling-chambers T U W in the box S, which is filled with water of the desired temperature (generally cool or cold) to condense the vapors or such part of them as may be desired, and to cool the oils from the fractional condenser.

The box S with its contents forms what is hereinafter termed the "condenser" and "cooler." The different apparatus may be supported by

any appropriate means—such as brackets, beams, pillars, or the like—as well understood by mechanics accustomed to build this class of apparatus.

5 The operation is as follows: The still A having been filled with the oil to be distilled, and the fire started, the vapors pass off through the mass of stone C, which intercepts any particles which may be carried off mechanically by the current. The vapors, freed from these particles, pass off by the pipe E into the manifold G, and are distributed to the columns, up which they pass to escape by the pipes Q into the coils or cooling chamber T, and be therein condensed. As the vapors pass into the manifold G and up the lower sections of the columns H the heaviest vapors are condensed, and, collecting upon the rings I and disks K, they drip or run from one to the other, falling through the mixed vapors, and assisting in condensing and separating the heaviest from the other vapors. This heavy oil, or oil of high boiling-point, collects in the manifold G, and thence passes off by the pipe N to the coils or chamber W, wherein it is cooled. The vapors, having parted with their heaviest portion, pass through the upper sections of the columns, and the second grade of vapors are therein condensed by the lower temperature, assisted by the condensed oil dripping from disk to ring and ring to disk. The oil is carried off by the pipes P into the coils or cooling-chamber U. The three grades of oil from chambers T U W are delivered into any suitable receptacles for storage or other purposes.

It is evident that by duplication or extension of the apparatus described more than three grades of oil may be produced. It is also evident that modifications may be made in details without departing from the spirit of the invention, and parts of the invention may be used separately.

I am aware that heretofore in distilling it has been proposed to employ in the upper part of the still, or in a chamber communicating therewith, a body of pumice-stone, fine pebbles, or other porous or granular material, by which the vapors are to be deprived of a portion of their impurities; but such fine material as would be adapted to this purpose, where the object is to atomize the vapor, would be unsuited to the purposes of the present invention, because it would create a back-pressure apt to cause explosion of the oil still or detrimental to an effective distillation, or both. As already pointed out, I use irregular blocks of considerable size—say four or five inches in diameter—in a dome of such area that paths between the blocks are of a size and number to offer no appreciable resistance to the passage of the vapors while still effective to induce the precipitation of particles of liquid held in suspension in sequence of their irregularity or tortuous course, and these blocks are placed in imme-

diate proximity to the still, so as to avoid, so far as possible, condensation of the hydro-carbon vapor by cooling.

I am also aware that a fractionating condenser for oil stills has been made or proposed in which the vapors pass successively through a series of communicating chambers, each provided with its individual outlet for drawing off the condensed oil; but in this old apparatus the condensed liquid mainly or wholly flows down the vertical walls of the chambers, and the vapors are not exposed to showers or streams of condensed liquid falling through them, as it is exposed in the apparatus herein-before described to the liquid falling from ring to disk and disk to ring. Moreover, in the present invention, the vapor as it passes through the space between a ring and disk is treated to a shower or stream of the condensed liquid, and, as in passing through each column or distinct section of a column the vapor passes through many such spaces, it is subjected to a succession of such showers or streams for each grade of oil to be produced.

I am further aware that a series of alternating rings and disks has been used in different apparatus—as for example, in the column of an ammonia-still and in a washing apparatus for separating ammonia from the products of the destructive distillation of organic matter; but in none of these old apparatus are the operation and effect the same as in the present invention. In none of them are mixed vapors separated by successive partial condensations. Much less are liquids of gradually-diminishing temperature, the results of the successive partial condensations, utilized to effect a further condensation of the proper vapors at each stage in virtue of their affinity for said vapors by causing them to fall from ring to disk and disk to ring through the mixed vapors.

Moreover, I am aware that a series of perforated disks strung on a rod have been supported freely, so as to be removable at will in a condenser-column; but a system of alternating and connected rings and disks adapted to be freely supported is believed to be new.

Having now described the invention and the manner in which the same is or may be carried into effect, what I claim, and desire to secure by Letters Patent, is—

1. An oil-still having in immediate proximity to the still and in free communication therewith a dome of the proportions and filled with irregular blocks or pieces of about the size stated, and having also the vapor-escape pipe leading from said dome, so that the hydro-carbon vapors in leaving the still pass by tortuous paths without appreciable resistance through material of practically the temperature of the boiling oil, and deposit thereon any particles of liquid held in suspension without being themselves condensed to a material extent, substantially as described.

2. In combination with an oil-still, columns

- or sections of a column connected in series and receiving in succession the mixed vapors from the still, each column or section being provided inside with a series of alternating disks and 5 rings, and having its individual outlet at the bottom, so that the oil is drawn off separately as distillates of different fire-test from the different columns or sections, substantially as described.
- 10 3. A column or upright pipe divided by an offset or bend into sections having each a series of rings and disks inside the same, and provided with separate outlets for the condensed liquid or oil, substantially as described.
- 15 4. An apparatus comprising tubular parts or sections of a column placed at different levels and connected in series, so that the vapors pass through them successively, and immersed in or surrounded by a common medium 20 for lowering the temperature in said parts or sections, each part or section being provided with its own liquid outlet and with a series of alternating rings and disks inside the same, substantially as described.
- 25 5. The combination, with a still, of a group of parallel columns having inlets at the bottom and outlets at the top, a box containing said columns, a series of alternating rings and disks in each column, a manifold at the lower 30 ends of said columns, a vapor-pipe leading from the still to said manifold, and a pipe for drawing off the liquid from said manifold, said columns communicating with a common chamber in said manifold, so that the vapor may 35 pass at once into all the columns, substantially as described.
6. The combination, with the inclosing pipe or column, of the rings and disks, the tie-rods, the separating sleeves, and the suspending plate or frame, substantially as described. 40
7. In the fractional condensation of hydro-carbon vapors by passing the vapors successively through a number of columns or sections of a column, so as gradually to lower the temperature of the vapors, and drawing off the 45 condensed liquid from each column or section separately, the improvement consisting in exposing the vapors in each chamber to a succession of showers or streams of the liquid condensed in that chamber, and thus effecting the 50 desired successive partial condensations by repeated exposure of the vapors to hot hydro-carbon liquid approximating the vapors in temperature, and, like them, gradually diminishing in temperature for each column or section, 55 as well as by the lower temperature in each column or section, the said improvement being carried out in an apparatus—such as the series of columns or sections provided inside with alternating rings and disks and immersed 60 in or surrounded by a hot medium—calculated to induce a gradual reduction of the vapors in temperature, and to effect a repeated contact between the vapors and the condensed liquid, 65 substantially as described.

In testimony whereof I have affixed my signature in presence of two witnesses.

HERMAN FRASCH.
